COMPUTER MEMORY SYSTEM

Donald A. Meier, Inglewood, Calif., assignor to The National Cash Register Company, Dayton, Ohio, a corporation of Maryland

Filed Mar. 26, 1963, Ser. No. 268,145

7 Claims. (Cl. 340—174)

The present invention relates generally to digital computer memory systems, and more particularly to an improved bistable memory matrix arrangement and construction.

With the ever increasing use of digital computers in science and industry, considerable attention has been directed towards providing improved memory systems for use therewith. It is the broad object of the present invention to further advance the state of the art of such memory systems.

An important feature of a memory system relates to its speed of operation, particularly in view of the efforts which have been directed towards increasing the speed of computer operation as much as possible. Accordingly, it is an object of the present invention to provide a memory arrangement and construction which is capable of high speed operation.

In addition to high speed operation, it is also of importance that a memory system be of simplified and economical construction, since the cost of a memory is often a significant part of the cost of an entire computer. Accordingly, it is another object of the present invention to provide an improved memory construction arrangement which is economical of components as well as being of relatively simple design.

Still further problems with regard to memory systems arise because of unwanted noise which interferes with the reliable sensing of signal information and often prevents achieving high speed operation and/or a high packing density. Such noise may result from the coupling of energy between adjacent memory bits, or may result because of the changing pattern of signal information. In any case, noise must be taken into account in the design of a memory system and, accordingly, it is another object of the present invention to provide a memory system which advantageously handles the noise problem.

Yet another factor which must be considered in memory systems involves the manner in which information in a memory is sensed, and the present invention is also directed to providing improvements in such sensing means.

The manner in which the improvements stated in the above objects may be provided in a memory system in accordance with the present invention will be illustrated with respect to a particular embodiment employing bistable memory elements comprised of thin film rods having solenoidal windings thereon, as disclosed, for example, in the commonly assigned patent applications Ser. No. 795,934, now Patent No. 3,228,012, filed Feb. 27, 1959 and Ser. No. 77,451, now Patent No. 3,213,431 filed Dec. 21, 1960. It is to be understood that although the features of the present invention are of particular advantage when used in a thin film rod memory as disclosed in said applications, all of the features are not restricted to such use, and various features of the invention may also be used to advantage in other types of embodiments.

With respect to memories employing such thin film rods as disclosed in the aforementioned patent applications, it is a still further object of the present invention to provide an improved construction and arrangement therefor.

The specific nature of the invention, as well as other objects, uses and advantages thereof will become apparent from the following description of a typical embodiment

2

of a thin film rod memory embodying the invention and illustrated in the accompanying drawings in which:

FIG. 1 is a perspective view, partially broken away, of a typical thin film rod and its associated windings;

5 FIG. 2 is a perspective view of a portion of FIG. 1 and will be used in describing the mode of operation of a basic magnetic element;

FIG. 3 is a graph illustrating the hysteresis characteristic of the thin film magnetic material provided on the rod of FIGS. 1 and 2;

FIG. 4 is a fragmentary perspective view illustrating how the rods of FIGS. 1 and 2 are arranged in a three-dimensional matrix array;

10 FIG. 5 is a series of graphs which will be used in explaining the operation of the invention;

FIG. 6 is an electrical circuit diagram illustrating the operation of a typical row grounder and column driver in accessing the word windings of a particular matrix word cell of the matrix of FIG. 4;

FIG. 7 is an electrical circuit diagram illustrating the connection and operation of the sense-digit windings in a typical digit plane in the matrix of FIG. 4;

FIG. 8 is an electrical circuit diagram illustrating a typical digit plane sense amplifier;

25 FIG. 9 is a graph which will be used in explaining the operation of the sense amplifier of FIG. 8;

FIG. 10 is an electrical circuit diagram illustrating how the sense-digit windings of a digit plane in the array of FIG. 4 may be partitioned; and

30 FIG. 11 is a perspective view illustrating how the matrix array of FIG. 4 may be disposed in an appropriate housing so as to have a bias magnetic field applied thereto.

Referring first to FIGS. 1 and 2, the basic thin film rod 10 and its associated windings are illustrated. A plurality of such rods are arranged in a three-dimensional matrix to form the thin film rod memory which will be used to exemplify the features of the present invention. As shown in FIG. 1, the rod 10 is comprised of an inner conductive substrate 12 on which is provided a thin film magnetic coating 14. Typically, the substrate 12 may be a beryllium copper rod of about 0.010 inch in diameter, but in any case, preferably less than 0.10 inch in diameter. The thin film magnetic coating 14 may typically comprise a bilayer magnetic film of the type disclosed in the aforementioned copending commonly assigned patent application Ser. No. 77,451—namely, a first adherent iron-nickel layer electrodeposited on the beryllium copper rod and composed of from about 30% to about 90% nickel and from about 70% to about 10% iron, and a second adherent iron-nickel layer electrodeposited on the first layer and composed of from about 93% to 99% iron and from about 7% to 1% of nickel, the composite thickness typically ranging from about 2,000 to 8,000 angstroms, but in any case, preferably less than 10,000 angstroms. Such a composite bilayer magnetic film has a substantially rectangular hysteresis characteristic and may typically have a coercive force of about 8 oersted, an anisotropy field of about 12 oersted, and a switching time of approximately 25 nanoseconds (that is, 25×10^{-9} seconds). Also, the first adherent iron-nickel layer preferably has a uniaxial oriented easy direction.

Still referring to the basic rod of FIG. 1, it will be seen that the various windings associated with the rod 10 are as follows: (1) a sense-digit winding 11 wound along the length of the rod and, as will be explained hereinafter, serves as both a sense and a digit winding, and (2) a plurality of nine spaced word windings 21, 22 . . . 28, and 29 wound over the sense-digit winding 11 and capable of receiving applied currents by way of respective word lines 31, 32 . . . 38 and 39.

As also indicated in FIG. 1, the lead 11b at the free end of the sense-digit winding 11 nearest the back of the rod (as viewed in FIG. 1) is connected (such as by soldering) to the back of the inner conductive substrate 12 so as to connect the sense-digit winding 11 and the substrate 12 in series. Similarly, the front of substrate 12 has a wire 12a soldered thereto at typical solder joint 12b, the wire 12a being provided to permit the series-connected digit-sense winding 11 and substrate 12 to be connected to the series-connected digit-sense winding and substrate of other rods in the matrix. From the above, it should be evident that a current applied to lead 11a at the free end of the sense-digit winding 11 nearest the front of rod 10 will flow through the sense-digit winding 11 wound along rod 10, through the lead 11b at the back end of the rod 10, then through the conductive substrate 12 in the opposite direction, until the current appears at the front end of substrate 12, where it will then flow by way of lead 12a to other series-connected sense-digit windings and substrates in the matrix. The advantages of connecting the sense-digit winding 11 to the inner substrate 12 will be considered further on in this description when the mode of operation is considered.

However, before considering the three-dimensional matrix which is formed of rods and associated windings such as typically illustrated in FIG. 1, the mode of operation of the basic magnetic storage element (a plurality of which are provided on each rod) will first be considered with reference to FIGS. 2 and 3 along with FIG. 1. The typical basic magnetic storage element is the portion of the thin film magnetic coating 14 which is in the immediate vicinity of each of the word windings 21 to 29 shown in FIG. 1. Since each basic magnetic storage element is the same, it is sufficient for explanatory purposes to merely consider the magnetic film in the vicinity of word winding 21, which is the portion shown in FIG. 2. It will be understood that the magnetic film provided on the rod has a rectangular hysteresis characteristic, such as illustrated in FIG. 3, and an elemental portion thereof (such as the portion shown in FIG. 2) may be switched between its two states of saturation by the application thereto of suitable magnetic fields, such as produced by currents applied to its respective word winding 21 and/or sense-digit winding 11. As indicated in FIG. 3, the two saturation states of the basic storage element may arbitrarily be designated as "1" and "0." Then, as is conventional, "reading" of data stored in a magnetic element may be accomplished by driving the element to the "0" saturation state and observing whether an output pulse is induced in the sense-digit winding 11 as a result of switching—a "1" being indicated when an output pulse is produced, and a "0" being indicated when the output signal is absent. As is also conventional, "writing" is caused to take place immediately after "reading," the magnetic element being left in the "0" state in which it resides after "reading" if a "0" is to be stored, and being driven to the "1" state if a "1" is to be stored. With the above as background, the specific mode of operation employed in the typical embodiment being described herein will now be described in detail with reference to FIGS. 2 and 3.

As indicated in FIG. 3, in the absence of currents applied to the word winding 21 and the sense-digit winding 11 (that is, when I_R , I_w , and I_D in FIG. 2 are all zero), an applied bias magnetic field H_B causes the basic element to reside at either point A or point A' in FIG. 3, depending upon whether the element is in the "1" or "0" state. This bias magnetic field H_B is applied in the "0" (or read) direction with a magnitude of about $\frac{1}{3}$ the field required for switching. Such a bias field H_B can be provided in various ways, such as by an additional bias winding (not shown), or by subjecting the rod to an external bias field, the latter being the approach used in the present invention and will be considered later on in this description.

Considering the reading operation with reference to FIGS. 1 to 3, the mode of operation is such that reading is accomplished using only the bias field H_B and the field H_R produced by applying a suitable read current I_R to the word line containing the word winding whose respective magnetic element is to be read out. The sense-digit winding 11 does not receive current during reading, its purpose being only to receive the induced pulse if the magnetic element switches. Thus, in FIG. 2, to read out the magnetic element associated with word winding 21, read current I_R would be applied to word line 31, producing the read drive field H_R in FIG. 3 which, in conjunction with the bias field H_B , is sufficient to drive the magnetic element into the "0" saturation state, as indicated at the point E in FIG. 3. If the magnetic element is in the "1" state prior to reading (in which case it would be residing at point A in FIG. 3), the drive field H_R drives the element from point A to point E in FIG. 3 so as to switch the element from "1" to "0," and thereby induce an output signal in the sense-digit line 11 to indicate the storage of a "1." If, on the other hand, the magnetic element is already in the "0" state prior to reading (in which case it would be residing at point A' in FIG. 3), then it would merely be driven from point A' to point E in the same "0" saturation state, so that no output signal (or negligible output signal) would be induced in the sense-digit winding 11 to indicate the storage of a "0." In order to speed up the time required for switching as well as to increase reliability, it is preferable, as indicated in FIG. 3, to choose the value of the current I_R applied to the word line so that a drive field H_R is produced which is significantly in excess of the minimum required for switching. This can safely be done since, as will become evident hereinafter, the organization of the memory matrix using rods such as illustrated in FIG. 1 employs linear selection for selecting word lines so that sufficiently large read currents I_R can be applied to the selected word line without causing switching of unselected magnetic elements.

From the foregoing explanation of the reading operation, it will be understood that after reading, the magnetic elements will reside in the "0" state at point A' in FIG. 3 regardless of whether it previously stored a "1" and "0." Operation is thus of the destructive readout type since, as a result of reading, the information contained in the magnetic element is lost. Writing of the previous information back into the magnetic element, or the writing of new information, is then caused to occur immediately following the reading operation, as is typical in most destructive readout magnetic memories. Writing is accomplished by applying a write current I_w to the same word line which was selected during the reading operation (which is word line 31 in FIG. 2). The write current I_w flowing through word winding 21 produces the magnetic field H_w indicated in FIG. 3, which drives the magnetic element from point A' in FIG. 3 to point C, about $\frac{1}{3}$ of the way towards the "1" state, but still not sufficient by itself to change the state of the element. If a "1" is to be written, the additional magnetic field required to switch the element is provided by applying a digit current I_D to the sense-digit winding 11 (as indicated in FIG. 2) to drive the magnetic element the remaining $\frac{2}{3}$ of the way to the "1" state, as indicated at point D in FIG. 3. If, on the other hand, a "0" is to be written into the magnetic element, no digit current is applied to the sense-digit winding 11. As a result, the magnetic element is driven only to point C by the field H_w produced by write current I_w , and the element remains in the "0" state after writing is completed to thereby store a "0." From the foregoing it will be understood that during the typical writing operation being considered, the write current I_w is always applied to the selected word line following a reading operation, but the digit current I_D is applied to the sense-digit winding 11 only if a "1" is to be written.

The manner in which the above described mode of operation fits in with the overall rod memory organization will be considered later on in this description when the entire three-dimensional memory is considered. However, before leaving the description of the basic rod and its mode of operation, an important feature of the particular embodiment of the rod illustrated in FIGS. 1 and 2 will first be considered. It will be remembered that the sense-digit winding 11 is continuous along the rod 10 so that digit current I_D (which is provided during writing if a "1" is to be written) flows continuously along the winding to lead 11b (FIG. 1) and is returned to the front of the rod by way of the inner conductive substrate 12, as indicated in both FIGS. 1 and 2, the digit current then being passed on to the sense-digit windings and substrates of other rods by way of lead 12a soldered to the inner substrate 12 at solder joint 12b. Such a construction has a number of important advantages. First, the use of the inner conductive substrate 12 as a return path is quite advantageous in that it reduces the necessity of providing an additional return winding, thereby greatly simplifying the construction and arrangement of such rods in a matrix. In addition, since the digit current I_D flows through the inner substrate 12, a transverse field is produced (that is, a circular magnetic field emanating from substrate 12) which is in addition to the axial field produced by the pitch of the sense-digit winding 11. This transverse field is, of course, less than the anisotropy field, but has the advantageous effect of reducing the amount of axial field that would ordinarily be required, and thereby permits the use of a considerably smaller digit current I_D during the writing operation, which may typically be as much as 25% smaller.

A still further and perhaps the most important advantage of causing digit current to flow in the inner conductive substrate 12 is that the circular or transverse magnetic field produced thereby acts to cancel the circular magnetic field produced around the rod by the pitch of the sense-digit winding 11. As a result, there will be no external circular magnetic field to couple to adjacent rods, which is important since the spacing between rods in the rod matrix can now be greatly decreased so as to achieve a high packing density.

At this point it may also be noted that not only is coupling due to circular magnetic fields practically eliminated, but also, because of the relatively small diameter of the rods (that is, of the order of .010 inch), the problem of axial field coupling between adjacent rods is also very greatly reduced, since the cross-sectional area of each rod is so small that it will not couple enough of the external field produced by the solenoid of an adjacent rod to have any significant effect. Thus, it will be appreciated that the rod construction illustrated in FIGS. 1 and 2 greatly reduces noise produced as a result of coupling between adjacent rods, the small diameter of the rod reducing axial field effects, and the return path for the digit current through the conductive substrate 12 reducing circular field effects.

It is to be noted that while the use of the inner conductive substrate 12 for a return line in FIGS. 1 and 2 has been exemplified with respect to the sense-digit winding 11, this type of rod construction can also be used to advantage with other types of windings and driving arrangements. For example, if the word windings were connected in series along the length of the rod 10 in FIG. 1, the conductive substrate 12 could be used for the return path, just as it is for the sense-digit winding 11 in FIG. 1. It is also to be noted that the sense-digit line need not be a continuous winding as indicated in FIGS. 1 and 2, but could also comprise a plurality of spaced windings connected in series and located below their respective word windings. In any case, for the purposes of this description and the appended claims the phrase "a plurality of series-connected windings" will be used to refer either to a con-

tinuous sense-digit winding as shown in FIGS. 1 and 2, or a series-connected plurality of spaced windings.

Having described a typical rod, its associated windings, and its basic mode of operation with reference to FIGS. 1 to 3, the overall three-dimensional array employing a plurality of such rods will next be considered with reference to FIG. 4 which is a perspective fragmentary view thereof. Thus, referring to FIG. 4, the rods are arranged so as to form a rectangular three-dimensional matrix comprised of eight vertical planes of rods with twenty rods being provided in each plane. In order not to confuse the figure, only rods in the extreme left and right hand vertical planes of the matrix are shown in FIG. 4, and of these, only the top two rods, the middle two rods, and the bottom two rods are shown. However, from this showing in FIG. 4 the overall arrangement will readily be understood. The memory organization is such that 8-digit words are stored in the matrix along lines perpendicular to the rod axes. As is well known, a word in computer technology merely represents a convenient number of binary digits which are grouped together. As a result of such an organization of words in the matrix, the vertical planes in FIG. 4 may be designated as digit planes, the extreme left and right planes in FIG. 4 being designated digit plane D_1 and digit plane D_8 , respectively. The term digit plane is used for these vertical planes, since this word organization causes each vertical plane to store the same corresponding digit for all words in the array. For example, each of the magnetic elements of rods located in digit plane D_1 will store the first digit of a respective 8-digit word in the array, while each of the magnetic elements of rods located in digit plane D_8 will store the eighth (or last) digit of a respective 8-digit word.

Before proceeding further with the description of the matrix of FIG. 4, the nomenclature employed therein will be explained to aid in the description to follow. Considering the rod designations, each rod is designated by the letters R and D having subscripts which represent the row and digit plane, respectively, in which the rod is located, a row being considered as including all rods which are in the same horizontal plane, as seen in FIG. 4. For example, the rod in the first row of digit plane D_1 is designated rod (R_1D_1) , the rod in the last (twentieth) row of digit plane D_8 is designated rod $(R_{20}D_8)$, and so on.

Considering the sense-digit winding next, since each is individual to a respective rod, it is given the same designation as the rod, but using the lower case letters r and d . Thus, the sense-digit winding on rod (R_1D_1) which is in the first row of digit plane D_1 is similarly designated as sense-digit winding (r_1d_1) .

Finally, considering the nomenclature used for the nine word windings on each rod, each word winding is designated by the three letters C, R and D with appropriate subscripts. The R and D letters of each word winding designation represent the particular rod on which the winding is wound, and thus are given the same subscripts as the rod. The C letter of the word winding designation represents which of the nine possible column positions on the rod that the word winding is located, there being nine word windings on each rod and, thus, nine possible word winding column positions. All windings having the same position on their respective rods are considered as being in the same column (numbered C_1 to C_9 from front to back in the matrix in FIG. 4) and the C letter of each word winding designation is therefore provided with a subscript which is numbered in accordance with the column position thereof. For example, the first word winding of the first rod in digit plane D_1 will be referred to as word winding $(C_1R_1D_1)$, the letters R_1D_1 indicating that the word winding is on rod (R_1D_1) and the letter C_1 indicating that the word winding is in column C_1 . It is to be noted in FIG. 4 that the nine columns of word windings C_1 to C_9 form planes which are perpendicular to both the eight digit planes D_1 to D_8 and the twenty row planes R_1 to R_{20} .

Having explained how the rods, sense-digit windings and word windings in the thin film rod matrix of FIG. 4 are designated, the manner in which the various windings are connected and driven will now be described. Considering the word windings first, it will be seen from FIG. 4 that each group of eight word windings (corresponding to a respective word stored in the matrix) which are located in both the same row and column are connected in series by a respective word line, the word line being designated by the letters R and C with subscripts which represent the particular row and column to which the word line corresponds. For example, the group of eight word windings $(C_1R_1D_1), (C_1R_1D_2) \dots (C_1R_1D_8)$ in column C_1 and row R_1 are all connected in series by word line C_1R_1 , and the eight magnetic elements respectively associated therewith may be considered to constitute a memory cell for the storage of an 8-digit word in the matrix at that column-row location. The address of the word cell may conveniently be designated in accordance with its column-row location in the matrix, and this is done using the lower case letters c and r. Thus, the address of the cell constituted by the magnetic elements associated with the word winding $C_1R_1D_1$ to $C_1R_1D_8$ will be designated word cell (c_1r_1) . Since there are nine columns C_1 to C_9 and twenty rows R_1 to R_{20} in the exemplary matrix of FIG. 4, the total storage capacity is 180 words, each word being eight digits long in correspondence with the eight digit planes D_1 to D_8 .

Still referring to the matrix of FIG. 4, it will be seen that the ends of the word lines at the left side of the matrix (as seen in FIG. 4) are connected together to form twenty rows which are in turn respectively connected to row grounders R_1 to R_{20} , the grounding lines from these row grounders each being designated in accordance with the row grounders to which it corresponds. The other ends of the word lines at the right side of the matrix are connected together through respective diodes $10a$ to form nine columns C_1 to C_9 which are in turn respectively connected to nine column drivers C_1 to C_9 and, as for the row grounding lines, the column drive lines are also each designated in accordance with the column driver to which it corresponds. It will be understood that such a connection of windings is in accordance with the well known linear selection approach to memory organization in which current can be caused to flow in a single selected word line by activating a particular one of the column drivers C_1 to C_9 and a particular one of the row grounders R_1 to R_{20} . For example, activation of column driver C_2 and row grounder R_8 results in the selection of word line (C_2R_8) , since only this line will have a completed path (through respective diode $10a$, column driver C_2 and row grounder R_8) for the flow of current therethrough. As is also well known with regard to linear selection systems, respective diodes $10a$ are provided in each word line in order to prevent sneak currents from flowing in unselected lines. It should thus be evident that in order to provide the read and write currents I_R and I_W required for the mode of operation previously described in connection with FIGS. 2 and 3, it is merely necessary to design the column drivers and row grounders so as to be capable of supplying the desired respective read and write currents I_R and I_W , and then to suitably activate, during appropriate read and write periods, the particular column driver and row grounder which correspond to the column-row of the cell in the matrix which is to be accessed.

Considering now the connection of the sense-digit lines in the matrix of FIG. 4, it will be remembered, as previously described in connection with FIG. 1, that the sense-digit winding 11 of each rod is wound continuously along the rod until it reaches the back end thereof, where lead $11b$ thereof is soldered to the inner conductive substrate 12 to permit digit current to flow therethrough and return to the front of the rod, a lead $12b$ being soldered at the front end of the substrate to permit connection to

the other sense-digit windings. As shown in FIG. 4, eight digit drivers D_1 to D_8 are provided, one for each digit plane, in order to provide for digit current flow in the event that "1" is to be stored in the selected magnetic element of each digit plane during the writing operation. The manner of connection of the sense-digit windings and substrates of rods in the same digit plane is such that, in each digit plane, the sense-digit windings and substrates of the top ten rods are connected in series across the respective digit driver by way of the top winding $100a$ of transformer 100 and, in a like manner, the sense-digit windings of the bottom ten rods are connected in series across the respective digit driver by way of the bottom winding $100b$ of transformer 100 . Thus, in each digit plane, the ten series-connected top sense-digit windings and substrates form one series circuit, and the bottom ten series-connected sense-digit windings and substrates form another series circuit, the two series circuits so formed being connected in parallel with respect to the digit driver of the digit plane by way of a respective winding of transformer 100 , the transformer windings $100a$ and $100b$ serving as inputs to a respective digit plane sense amplifier, as will be considered, hereinafter. For example, in digit plane D_1 , the sense-digit windings (r_1d_1) to $(r_{10}d_1)$ of the top ten rods (R_1D_1) to $(R_{10}D_1)$ are connected in series, as are the sense-digit windings $(r_{11}d_1)$ to $(r_{20}d_1)$ of the bottom ten rods $(R_{11}D_1)$ to $(R_{20}D_1)$ and each of the two resulting series circuits is connected across digit driver D_1 by way of a respective winding of transformer 100 . Such a connection of sense-digit windings and substrates in each digit plane is provided in order to obtain common mode rejection for noise cancellation purposes, as will be considered further on in this description. As will also be considered, hereinafter, a digit noise cancelling bridge network 105 formed of diodes 102 and resistors 104 serves during digit current flow to prevent varying information patterns of the magnetic elements of the top and bottom halves of the digit plane from producing unbalanced signals which would overdrive the sense amplifier and introduce recovery time problems that could limit the operating frequency of the memory.

The manner in which the above described matrix organization fits in with the earlier described mode of operation of a magnetic element will now be considered with reference to FIGS. 2 to 4 and the graphs of FIG. 5. In this connection, it should be understood that the particular physical arrangement of the rods and windings illustrated in the matrix of FIG. 4 can be modified, the important factor being the functional arrangement of the matrix with respect to the electrical operation to be provided. Reviewing, briefly, the previously described mode of operation, it will be remembered that during reading, read current I_R is caused to flow in the selected word line by activating the particular column driver and row grounder which correspond to the column-row address in the matrix of the word cell which is to be accessed. Since a continuous axial bias field H_B of the order of $\frac{1}{3}$ of the field required for switching is continuously applied to the matrix in the read direction, the read current I_R need only supply the remaining $\frac{2}{3}$ field. However, as indicated in FIG. 3, the read current I_R is chosen so that a significantly greater field H_R is produced during reading, which is advantageous because it results in a faster switching time. This greater read current can be provided in the matrix of FIG. 4, since all the magnetic elements of a word cell are always read out during reading, and the use of a linear selection approach causes the read current I_R to flow only in the selected word line. Consequently, during reading of the magnetic elements in the selected word cell, all other magnetic elements of unselected word cells remain undisturbed.

In FIG. 5, graph A illustrates a typical memory access start pulse which may occur in a computer (not shown) in which the memory matrix of FIG. 4 may be employed.

During such a start pulse, the computer performs various preparatory operations, such as setting up the address of the word cell in the matrix which is to be accessed, clearing the flip-flops which are to receive the data read out, preparing the data which is to be written into the accessed cell, etc. After these preliminary operations are completed, the computer may then provide suitable activation pulses, such as illustrated in graphs B and C in FIG. 5 to activate the particular column driver and row grounder which correspond to the address of the matrix word cell to be accessed. A typical resulting read current I_R flowing in the word windings of a selected word cell is illustrated in graph D and, as described previously in connection with FIGS. 2 and 3, serves to drive the magnetic elements of the selected word cell to the "0" state. Typical signals induced in the sense-digit windings during reading are illustrated in graph E of FIG. 5, the signal designated "1" representing the output pulse induced in a respective sense-digit winding when a magnetic element stores a "1," and the signal designated "0" representing the much smaller pulse induced in the respective sense-digit winding when a magnetic element stores a "0."

Since the matrix organization is such that only one magnetic element can ever be switched in each digit plane, only a single sense amplifier is required per digit plane, the sense amplifier serving to discriminate the "1" and "0" output pulses induced in the sense-digit line and, in response thereto, to make available to the computer suitable signals representative thereof. It will be understood that because the rod construction permits the sense-digit winding to have many turns, a relatively large amplitude "1" output pulse is produced which simplifies discrimination between such "1" output pulses and noise signals. It will also be understood that because the sense-digit windings are connected to each other and to the sense amplifier in common mode rejection fashion, capacitive-type noise resulting from electrostatic coupling between word windings and sense-digit lines will be essentially cancelled by input windings 100a and 100b of transformer 100. In order to take full advantage of this common mode rejection, it is preferable to turn on the selected row grounder slightly before the selected column driver, and turn off the selected row grounder slightly after the selected column driver, as indicated in graphs B and C in FIG. 5.

Turning now to a consideration of the writing operation, it will be remembered from the previous discussion in connection with FIGS. 2 and 3 that writing follows immediately after reading, and that the same previously activated column driver and row grounder operate during writing to cause write current I_w to flow in the same word line previously selected during reading. This write current I_w drives each magnetic element of the selected word cell approximately $\frac{1}{3}$ of the way to the "1" state (that is, to point C in FIG. 3), and since this is considerably less than the required switching field, each magnetic element will necessarily remain in the "0" state if no other magnetic field is applied, in which case, the magnetic element would indicate the storage of a "0" therein. Thus, to write a "0" in a magnetic element of the selected cell, its respective digit driver would be left unactivated (as indicated in graph G of FIG. 5) so that only the field produced by the write current I_w will be present.

On the other hand, if a "1" is to be written into a magnetic element of the selected word cell, its respective digit driver is activated to cause a digit current I_D to be concurrently applied thereto along with the write current I_w (as indicated in graphs D and G of FIG. 5). Each such magnetic element in which a "1" is to be written will thus receive the remaining $\frac{2}{3}$ drive field H_D (FIG. 3) required to drive it to the "1" state so as to thereby store a "1" therein. It is to be noted that the $\frac{2}{3}$ drive field H_D provided by the digit current I_D will not disturb the magnetic elements of unselected word cells which are coupled to the same sense-digit winding since no write current I_w flows through such elements. Consequently, the $\frac{1}{3}$ mag-

netic bias field H_B in the read direction will subtract from the $\frac{2}{3}$ digit field H_D to provide a resultant field in the write direction which is still only $\frac{1}{3}$ of the field required for switching.

Referring now to FIG. 6, a typical word plane of the matrix of FIG. 4 is illustrated, namely, the front word plane as seen in FIG. 4—that is, the word plane containing those word cells (c_1r_1) to $(c_{12}r_{20})$ whose word lines C_1R_1 to $C_{12}R_{20}$ are all connected to the first column driver C_1 . A typical embodiment of this column driver C_1 is shown in FIG. 6, as well as a typical embodiment of the row grounder R_1 , it being understood that the other column drivers and row grounders may be similarly constructed. The sense digit lines have been omitted in FIG. 6 for the sake of clarity.

For the description of FIG. 6 it will be assumed that word cell (c_1r_1) is to be accessed which is the one located in column C_1 and row R_1 of the matrix. Therefore, to access this word cell, row grounder R_1 and column driver C_1 are activated by the computer to provide the required read and write currents I_R and I_w through word line (C_1R_1) during respective reading and writing operations. To understand how this may typically be accomplished row grounder R_1 and column driver C_1 will be considered in more detail. Row grounder R_1 will be seen to comprise an NPN transistor 40 having its emitter grounded, its collector connected to word line (C_1R_1) , and its base connected to receive an activation signal, such as the signal 40a in graph B of FIG. 5, through a suitable base resistor. The transistor 40 normally resides at cut-off, and when activated becomes saturated so as to effectively ground the left side of all the word lines in row R_1 (that is, word lines C_1R_1 to C_9R_1 in FIG. 4), including word line (C_1R_1) which for the description of FIG. 6 is assumed as the line to be selected.

Column driver C_1 in FIG. 6 will be seen to comprise an NPN transistor 50 having its collector connected to a positive voltage source V_+ , and its emitter connected to a negative voltage source V_- through an appropriate emitter resistor. Like the row grounder transistor 40, the column driver transistor 50 is normally cut off, and when activated by the signal 50a shortly after the row grounder transistor 40 (as shown in graphs B and C of FIG. 5), a current path is completed through the selected word line (C_1R_1) . As a result, read current I_R flows (as indicated in FIG. 6) from column driver C_1 , through respective diode 10a, through word line (C_1R_1) and then through the emitter and collector of row grounder R_1 transistor 40 to circuit ground. Since current paths through all other word lines in the array are open, either because of an unactivated column driver or an unactivated row grounder, read current I_R flows only through the selected word line (C_1R_1) , the diodes 10a preventing the flow of "sneak" currents through other word lines.

Having described how read current I_R is applied to the selected word line (C_1R_1) by activation of row grounder R_1 and column driver C_1 , it will now be explained how the appropriate writer current I_w is provided during the write operation following thereafter. As mentioned previously, a respective diode 10a is employed in each word line to prevent sneak currents from flowing through unselected lines. This expedience is well known in linear selection systems. It is also known that diodes 10a may be chosen to have a relatively slow recovery time so that the minority carrier storage produced within the diode of the selected word line during reading may be used to obtain automatic writing in the same selected word cell as was accessed during reading, in a manner similar to a biased switch core. More specifically, it will be understood that by using an appropriate semiconductor diode for the diode 10a which has a slow recovery time, the minority carriers stored in the base of the diode 10a of the selected word line (C_1R_1) during reading will produce a reverse current (that is, a current in the write direction), if the selected word line is reverse-biased during writing. Where the

memory cycle is very fast of the order of 200 nanoseconds, as is typical for the thin film rod memory being considered herein, such a diode can advantageously be selected so as to have a recovery time commensurate with the period required for writing. Once this is done, it is merely necessary to choose the V_{-} voltage source and the emitter resistor of the transistor 50 in FIG. 6 to provide a suitable reverse bias which will produce the desired flow of write current I_w through word line (C_1R_1) following reading, as indicated in FIG. 6 and in graph D of FIG. 5. The diode 45 is provided across transistor 40 of row grounder R_1 to provide a path for the flow of write current I_w , since row grounder R_1 is cut off during writing.

Reference is now directed to FIG. 7 which shows a typical digit plane D_1 along with its associated digit driver D_1 , and its associated digit noise cancelling bridge network 105. The word windings on the rods have been omitted for greater clarity. The chief purpose of FIG. 7 is to explain how this digit noise cancelling bridge network 105 operates to prevent overdriving the sense amplifier during the flow of digit current as a result of varying information patterns in the top and bottom halves of each digit plane. It will be remembered that by series-connecting the digit-sense windings and substrates of the top ten rods in each digit plane to form a first series-connected circuit, and series-connecting the sense-digit windings and substrates of the bottom ten rods in each digit plane to form a second series-connected circuit, and then connecting each such series-connected circuit across the digit plane driver (D_1 in FIG. 7) by way of a respective winding 100a or 100b of transformer 100, the resulting symmetry provides common mode rejection for noise effects occurring in a like manner in each series connected circuit. Such common mode rejection not only serves during reading, as pointed out previously, but also serves during writing to cancel out the voltages produced across the two series-connected digit windings and substrates (that is, across $J-J$ in FIG. 7) as a result of the flow of digit current flow therethrough. Such cancellation is important from the viewpoint of the sense amplifier, even though the sense amplifier is not needed during writing, since noise voltages appearing across points $J-J$ can saturate the sense amplifier and prevent its recovering in time for the reading operation of the next memory cycle.

Since the digit current I_D divides between the two series-connected circuits formed from the top and bottom sense-digit windings, if the two series-connected circuits have identical impedances, the voltages appearing at points $J-J$ in FIG. 7 will provide perfect common mode cancellation. However, because the information pattern stored in the magnetic elements on the top and bottom rods may vary, one series-connected circuit may have a different impedance from the other so as to cause a voltage unbalance across points $J-J$, which will be applied to the digit plane sense amplifier. While the sense amplifier recovery time with such an unbalance may not be a problem in conventional memories having low repetition rates, it is very serious in memories where a high repetition rate is required, and the art is continually trying to increase memory repetition rate capability. It is an important feature of the present invention, therefore, to provide means, in addition to common mode rejection, which will automatically reduce the voltage unbalance applied to the digit plane sense amplifier during digit current flow as a result of varying information content in the two halves of the digit plane. Obviously, any such means has the further requirement that it must not interfere with the operation of the sense amplifier during reading. Such means are provided in the present invention in a remarkably simple manner using the bridge network 105 illustrated in FIG. 7 for the digit plane D_1 , it being understood that each of the other digit planes may be provided with a similar bridge network. As shown in FIG. 7, the diodes 102 and resistors 104 are connected to form a bridge with respect to the two series-connected sense

digit windings of the digit plane so that whenever digit current flow produces an unbalance across points $J-J$, diodes 102 will permit the digit currents flowing in each series-connected circuit to adjust by the amount required to eliminate this voltage unbalance. Slight differences between the digit currents flowing in the top and bottom sense-digit windings will, of course, occur but in the usual case, these differences will be so small as to be well within the tolerances of the thin film magnetic material characteristics.

It is to be noted with respect to the bridge network 105 of FIG. 7 that, as with most diodes, the high forward conductivity of diodes 102 will not be maintained below the diode threshold voltage. This threshold voltage will, thus, determine the maximum voltage unbalance which the bridge 105 will permit across points $J-J$, and must be high enough so that a "1" output pulse induced in a sense-digit winding during reading will pass to the sense amplifier. Typically, therefore, the threshold voltage of diodes 102 may be chosen of the order of 250 millivolts, which is larger than the "1" output pulse amplitude, but small enough so that the maximum unbalance voltage of 250 millivolts which can then appear across points $J-J$ will permit the sense amplifier to recover in time for the reading operation of the next memory cycle. The values of resistors 104 of the bridge network 105 are also chosen as a compromise between two values, the magnitudes of resistors 104 being sufficiently large to handle digit plane voltage unbalance during writing without causing significant differences in the digit currents flowing in each half of the digit plane, yet being sufficiently small so as not to significantly attenuate a "1" output pulse occurring during reading. The success of the bridge network 105 in preventing digit noise across points $J-J$ in FIG. 7 is illustrated in graph E of FIG. 5 by the relatively low amplitude signals 150 applied to the sense amplifier as a result of digit current flow during writing. Without the bridge network 105, these digit noise signals 150 would be of the order of 10 times larger.

Having considered the construction and operation of the thin film memory matrix of FIG. 4, the next area of consideration will be the sense amplifier provided in each digit plane. From the foregoing it will be evident that the function of each digit plane sense amplifier is to detect a "1" output pulse occurring in a sense-digit winding of its respective digit plane, while discriminating against "0" output pulses and other noise signals. In addition, the sense amplifier must also be able to recover after the writing operation is completed in sufficient time for the next reading operation. The manner in which an appropriate sense amplifier is provided in the present invention will now be considered in detail with reference to FIGS. 8 and 9.

Thus, referring to FIGS. 8 and 9, a typical digit plane sense amplifier in accordance with the invention is illustrated. The output windings 100c and 100d from transformer 100 (FIG. 7) are coupled by leads 110, 111 and 112 to input windings 200a and 200b of transformer 200 of the sense amplifier, one side of each of the output windings 200c and 200d being connected together to form junction 201. Lead 203 is connected to junction 201 for the purpose of permitting a read pedestal gate pulse 215, such as illustrated in graph F of FIG. 5, to be applied thereto for activating the sense amplifier, as will shortly be explained. The other side of windings 200c and 200d are connected to the plates of tunnel rectifiers 205 and 210, respectively, the cathodes of tunnel rectifiers 205 and 210 being in turn connected to the input of D.C. amplifier and shaper 225, across which is connected the inductor 214. It is to be understood that the arrangement of the windings of transformers 100 (FIG. 7) and 200 (FIG. 8) is such that the same common mode rejection obtained across input windings 100a and 100b of transformer 100 is also obtained across output windings 200c and 200d. The transformer 200, the tunnel rectifiers 205 and 210,

and the inductor 214 may be considered to constitute the sense amplifier input circuit 220 indicated in FIG. 8.

The operation of the sense amplifier input circuit 220 illustrated in FIG. 8, will now be considered with reference to FIG. 9, the specific curves and voltages illustrated in FIG. 9 being merely illustrative. It will be understood that tunnel rectifiers 205 and 210 may each have the typical current vs. voltage characteristic curve illustrated in FIG. 9, and each may typically be provided with a forward bias of 250 millivolts by way of lead 203, in which case they will each reside in a high forward impedance region. As indicated in FIG. 9, this high forward impedance region extends from about 0 to almost 500 millivolts. Thus, with the tunnel rectifiers forwardly biased to 250 millivolts, any signals appearing in winding 200c or 200d which are less than ± 250 millivolts will not drive the tunnel rectifiers out of their relatively high forward impedance region. Such input signals less than ± 250 millivolts will, thus, be blocked from reaching the amplifier and shaper 225. Since the bridge network 105 provided across each digit plane, as indicated in FIG. 7, limits signals to about ± 250 millivolts or less, it will be understood that the combination of this bridge network 105 with the sense amplifier input circuit 220 will advantageously prevent any matrix noise signals from reaching the D.C. amplifier and shaper 225. As a result, recovery problems in the D.C. amplifier and shaper 225 as a result of digit current flow are virtually eliminated.

In order to permit a "1" output pulse appearing in a digit plane during reading to be passed to the amplifier and shaper 225, the read pedestal pulse 215 is applied when a "1" output pulse is expected—that is, concurrently with the row grounder and column driver pulses 40a and 50a, as shown in graphs B, C and F of FIG. 5. As indicated in FIG. 9, the read pedestal pulse 215 acts to shift the bias of the tunnel rectifiers to 25 millivolts so that a "1" output pulse, which may typically be of the order of 75 millivolts, will drive a respective tunnel rectifier 205 or 210 into a region of relatively low impedance (as indicated in FIG. 9) so as to pass an output pulse of the order of -50 millivolts to the D.C. amplifier and shaper 225. Since, as pointed out previously, only one magnetic element at a time is ever selected for reading in any one digit plane, only one of the windings 200c or 200d will receive the "1" output pulse, depending upon which half of the digit plane that the selected magnetic element is located. Thus, only one of the tunnel rectifiers 205 or 210 is operated at a time to pass a "1" output pulse during a reading operation. The amplifier and shaper 225 operates in response to the -50 millivolt pulse passed thereto from either of the tunnel rectifiers 205 and 210 to provide a suitable output signal for use by the computer in which the memory is incorporated. The inductance 214 at the input of the D.C. amplifier and shaper 225 is chosen to be of sufficiently low D.C. impedance so that no D.C. restoration is required of a tunnel rectifier after passing the "1" output pulse. As a result, the input circuit 220 may be caused to typically recover within 50 nanoseconds after the fall of the read pedestal pulse 215.

Graph H of FIG. 5 illustrates typical signals applied to the amplifier and shaper 225 by the sense amplifier input circuit 220 during reading and writing, and clearly shows the high degree of discrimination and the absence of noise provided thereby. A further advantage of the use of tunnel rectifiers in the sense amplifier input circuit 220 illustrated in FIG. 8 is that, besides the high discrimination provided thereby, the back slope of the tunnel rectifier voltage vs. current characteristic (that is, for negatively applied voltages) is very temperature-stable and thus can provide reliable detection over a wide temperature range.

Because of the high order discrimination provided by the sense amplifier input circuit 220 illustrated in FIG. 8, it becomes possible to partition the various sense-digit windings into a greater number of series-connected cir-

cuits, rather than just the single pair of series-connected circuits illustrated in FIG. 7. Such an arrangement is highly advantageous when a digit plane incorporates a large number of magnetic elements, since it permits avoiding 5 transmission delays which could interfere with high speed operation. FIG. 10 illustrates how the sense-digit windings in a digit plane may typically be partitioned into "N" pairs of series-connected sense-digit windings, the pairs being designated P₁ to P_N, and being fed by a common digit driver 350. Each pair includes a respective bridge circuit 105 and a respective sense amplifier input circuit 220 operating as described for the single pair in connection with FIGS. 7 and 8, the outputs of the sense amplifier inputs 220 being fed in parallel to a common D.C. amplifier 15 and shaper 225'. Obviously, instead of using a single common digit driver, a separate digit driver could be provided for each pair, as illustrated for the single pair in FIG. 7.

The final figure to be considered is FIG. 11 which illustrates how the bias field H_B (FIGS. 1 to 4) may typically be applied to the matrix of FIG. 4. The approach employed involves disposing the matrix 307 in a suitable housing 305 having grooves 305a and 305b therein. Helmholtz-type coils 310 and 312 are wound in grooves 305a and 305b, respectively, and are connected in series by lead 311 so that their magnetic fields are additive. A bias current source 320 connected across coils 310 and 312 produces a bias current I_B therein of sufficient magnitude to provide the bias magnetic field H_B indicated in FIG. 3.

While the foregoing disclosure has been primarily concerned with particular illustrative embodiments, it will be appreciated that the invention is not limited to the specific uses or to the specific constructional arrangements disclosed herein, and is to be considered as including all modifications and variations encompassed within the scope of the appended claims.

What is claimed is:

1. In a magnetic memory array, a conductive rod substrate, a thin film magnetic layer coated on said substrate, at least one multiple-turn solenoidal winding encircling said layer, means connecting one end of said winding to one end of said conductive substrate, and means on said substrate and said winding providing an input for applying current between the other end of said conductive substrate and the other end of said winding.

2. In a magnetic memory array, a conductive rod substrate, a thin film magnetic layer coated on said substrate, at least one multiple-turn solenoidal winding encircling said layer, means connecting one end of said winding to one end of said conductive substrate, and means for applying current between the other end of said conductive substrate and the other end of said winding, the connections between said winding and said conductive substrate being such that the circular component of the magnetic field produced by current flowing in said winding and caused by the pitch thereof is in a direction opposite to the circular magnetic field produced by current flowing in said conductive substrate.

3. In a magnetic memory array, a conductive rod substrate having a thickness less than 0.1 inch, a thin film magnetic layer coated on said substrate having a substantially rectangular hysteresis characteristic and a thickness of about 2,000 to 10,000 angstroms, at least one multiple-turn solenoidal winding encircling said layer and tightly coupled thereto, means connecting one end of said winding to one end of said conductive substrate, and means for applying current between the other end of said conductive substrate and the other end of said winding, the connections between said winding and said conductive substrate being such that the circular component of the magnetic field produced by current flowing in said winding and caused by the pitch thereof is in a direction opposite to the circular magnetic field produced by current flowing in said conductive substrate.

60 4. In a magnetic memory array, a conductive rod substrate having a thickness less than 0.1 inch, a thin film magnetic layer coated on said substrate having a substantially rectangular hysteresis characteristic and a thickness of about 2,000 to 10,000 angstroms, at least one multiple-turn solenoidal winding encircling said layer and tightly coupled thereto, means connecting one end of said winding to one end of said conductive substrate, and means for applying current between the other end of said conductive substrate and the other end of said winding, the connections between said winding and said conductive substrate being such that the circular component of the magnetic field produced by current flowing in said winding and caused by the pitch thereof is in a direction opposite to the circular magnetic field produced by current flowing in said conductive substrate.

4. In a magnetic memory array, a conductive rod substrate, a thin film magnetic layer coated on said substrate, first and second multiple-turn solenoidal windings encircling said layer, one of said windings being wound on the other, means connecting one end of said first winding to one end of said conductive substrate, means for applying current between the other end of said conductive substrate and the other end of said first winding, and means for applying current to the second winding, the arrangement of said first and second windings on said substrate, the directions of applied current, and the connection of said first winding to said conductive substrate being constructed and arranged so that the circular component of the magnetic field produced by current flowing in said first winding and caused by the pitch thereof is in a direction opposite to current flowing in said conductive substrate, and such that the axial magnetic fields produced by current flowing in said first and second windings are in the same direction and act in conjunction with the transverse magnetic field produced by current flowing in said conductive substrate to provide sufficient magnetic field to switch the state of the portion of said magnetic layer in the vicinity of said windings.

5. The invention in accordance with claim 4, wherein said conductive rod has a diameter of less than 0.1 inch, and said magnetic layer has a thickness of about 2,000 to 10,000 angstroms.

6. In a magnetic memory array, a plurality of magnetic rods, each comprised of a conductive inner substrate having a thin film magnetic layer coated thereon and each including at least one solenoid winding, means connecting one end of the solenoid windings of at least two rods to its respective substrate, means connecting the other end of the substrate of one of said two rods to the solenoid winding of the other of said two rods so that the respective substrates and solenoid windings are in series, and means for applying a current to the series-connected solenoid windings and substrates, the connections therebetween being such that the circular component of the magnetic field produced by current flowing in each solenoid winding and caused by the pitch thereof is in a direction opposite to the magnetic field produced by current flowing in its respective substrate.

7. In a magnetic memory array, a plurality of magnetic rods functionally arranged in a plurality of digit planes, each magnetic rod being comprised of a conductive inner substrate having a thin film magnetic layer coated thereon and each including first and second pluralities of solenoid windings extending along the length of the rod, the solenoid windings from one plurality being wound over the solenoid windings from the other plurality, said first plurality of windings being connected in series, means connecting one free end of the series-connected windings of said first plurality on at least two rods in the same digit plane to its respective substrate, means connecting the other end of the substrate of one of said two rods to the other free end of the series-connected windings of said first plurality on the other of said two rods so that the series-connected solenoid windings and substrates are all in series, means for applying a current to the series-connected solenoid windings and substrates, the connections therebetween being such that the circular component of the magnetic field produced by current flowing in the series-connected windings of said first plurality of windings on each of said two rods and caused by the pitch thereof is in a direction opposite to the magnetic field produced by current flowing in its respective substrate, means connecting like-positioned ones of the second plurality of solenoid windings on rods in different digit planes in series, and means for applying current to a selected group of like-positioned series-connected windings.
